(57) **CLAIM**

The ornamental design for an illuminating device, as shown and described.

DESCRIPTION

FIG. 1 is a right front perspective view of the illuminating device;

FIG. 2 is a front elevation view thereof;

FIG. 3 is a right elevation view thereof;

FIG. 4 is a rear elevation view thereof;

FIG. 5 is a left elevation view thereof;

FIG. 6 is a top view thereof; and,

FIG. 7 is a bottom view thereof.

The broken lines shown on the drawings depict environment only and form no part of the claimed design.

Screw-type fasteners and pins and their respective receiving holes do not form part of the claimed design.

All depicted features behind (i.e. interior of) the hexagonal protective grid screen, except the lens, do not form part of the claimed design.

All depicted features shown inside the broad slots of the cylindrical housing do not form part of the claimed design.

All depicted features shown inside the slots in the front of the base do not form part of the claimed design.

All depicted features shown inside the plug connection in the lower right hand corner in the right elevation view does not form part of the claimed design.

The surface ornamentation on the housing mounting clips of the handle does not form part of the claimed design.
